UNITED STATES PATENT OFFICE.

WILLIAM H. BRISTOL, OF WATERBURY, CONNECTICUT, ASSIGNOR TO THE BRISTOL COMPANY, OF WATERBURY, CONNECTICUT, A CORPORATION OF CONNECTICUT.

INSTRUMENT-CASING.

1,099,115.

Specification of Letters Patent.

Patented June 2, 1914.

Application filed November 22, 1913. Serial No. 802,382.

To all whom it may concern:

Be it known that I, WILLIAM H. BRISTOL, a citizen of the United States, and a resident of Waterbury, in the county of New Haven 5 and State of Connecticut, have invented certain new and useful Improvements in Instrument-Casings, of which the following is a specification.

The invention relates to improvements in 10 casings for measuring instruments or gages, and more particularly to the cover or lid which is adapted to seal the interior thereof against the entrance of dust, moisture or other foreign material.

15 It has for its object to provide, of sheet metal of suitable thickness, a lid or cover for a casing; and which lid, though comparatively light, shall be sufficiently durable and reinforced to sustain the glass plate 20 as well as to afford ample material for attachment of a hinge. A saving of material is effected in the improved construction and a lighter weight cover produced, whereby stress on the hinge is reduced to a minimum.

25 A further object of the invention is to afford means to retain suitable packing to render the casing dust and moisture-proof.

The nature of the invention will be best understood when described in connection 30 with the accompanying drawings, in which—

Figure 1 is a front elevation of a pressure gage provided with the improved casing cover. Fig. 2 is a horizontal section there- 35 through, the gage mechanism being omitted.

Similar characters of reference designate corresponding parts throughout the several views.

40 Referring to the drawings, 10 designates a casing of suitable material and is shown cylindrical in form, said casing being adapted to retain the measuring apparatus 11 as is well understood. Apparatus thus mounted in a casing is usually of a sensitive nature 45 and requires protection from dust, moisture and other foreign materials; and for this purpose, there is generally hingedly connected to the casing a cover or lid such as the cover 12 herein shown, and which retains a glass front or plate 13. Heretofore, these 50 covers were constructed of suitable castings which necessarily rendered them heavy and which, moreover, required considerable machine work thereon to provide the necessary holding members and the desired finish.

It is the object of the present invention to provide a cover which may be rapidly and cheaply formed out of sheet metal; and for this purpose, the same is constructed of two parts—an outer ring 14 and an inner ring 15. The outer ring 14 is shaped to suit, having preferably an upper overhanging or outwardly flaring rim 16 of the doubled over portion of the material and an outer wall 17 extending inwardly toward and adapted 60 to fit over the edge of the casing 10. The inner wall 18 of said ring extends over the plate 13 with which it contacts, being turned slightly toward the casing. The inner ring 15 is channel shaped and is fitted within the 65 outer ring, being secured thereto by soldering at a number of points. The outer wall 19 of the ring 15 extends inwardly toward the casing 10 following the wall 17 for a portion of its length and is then turned away 70 from the same to provide a groove 20 adapted to retain suitable packing 21 resting, when the cover is closed, upon the edge of the casing to securely seal said casing against the entrance of dust, moisture and other foreign 75 material. The other wall or lip 22 of said inner ring affords an abutment for the glass plate 13 which is held in the cover by a suitable cement 23 and by flexible clips 24 which latter may be attached to the bottom 80 of the channel shaped ring 15 and extend under the glass to hold the same. The walls 17 and 19 at their contacting portions provide, moreover, sufficient material for the attachment for one leaf of a hinge 25, the 85 other leaf of which is attached to the casing 10.

I claim:

1. The combination with a cylindrical casing; of a cover therefor comprising an 95 outer channel shaped ring and an inner channel shaped ring of sheet metal fitting therein and suitably secured thereto, the outer sides thereof being separated at their edges to provide a packing groove to retain 100 suitable packing adapted to coöperate with the edge of said casing; and a plate held by said rings.

2. The combination with a cylindrical cas- 105 ing; of a cover therefor comprising an outer channel shaped ring and an inner channel shaped ring of sheet metal, fitting therein and suitably secured thereto and the outer sides thereof being separated at their edges to provide a packing groove to retain suit- 110

able packing adapted to coöperate with the edge of said casing; a plate held by said rings; and a hinge, one leaf of which is secured to the walls of both the said rings and the other to said casing, whereby the said cover is hingedly connected thereto.

3. The combination with a cylindrical casing; of a cover therefor comprising an outer ring and an inner ring of sheet metal, the former being doubled upon itself for a portion and flaring outwardly to provide a suitable rim for the cover and one wall thereof extending over the casing and the other toward the casing and adapted to fit

15 over the same, and the said inner ring having a wall extending toward said casing following the similar wall of said outer ring and offset therefrom at the edge thereof to afford a packing groove coöperating with 20 the edge of said casing; and a plate held by said rings.

4. The combination with a cylindrical casing; of a cover therefor comprising an outer ring and an inner ring of sheet metal, the former being doubled upon itself for a portion and flaring outwardly to provide a suitable rim for the cover and having one wall thereof extending over the casing and the other toward the casing and adapted to 25 fit over the same, and the said inner ring having a wall extending toward said casing following the similar wall of said outer ring and offset therefrom at the edge thereof to afford a packing groove coöperating with 30 the edge of said casing; a plate held by said rings; and a hinge, one leaf of which is secured to the two inwardly extending walls of the outer and inner rings and the other leaf to the said casing to hingedly connect 35 the cover thereto.

5. The combination with a cylindrical casing; of a cover therefor comprising an outer ring and an inner ring of sheet metal, the former having one wall thereof extending

over the casing and the other toward the 45 casing and adapted to fit over the same, and the said inner ring being channel shaped, one wall thereof extending toward said casing and following the similar wall of said outer ring and offset therefrom at its edge 50 to afford a packing groove coöperating with the edge of said casing, and the other wall of said channel shaped ring extending a short distance toward said casing to provide an abutment; and a plate held between the 55 wall of the outer ring extending over said casing and the said abutment.

6. The combination with a cylindrical casing; of a cover therefor comprising an outer ring and an inner ring of sheet metal, the former being doubled upon itself for a portion and flaring outwardly to provide a suitable rim for the cover and one wall thereof extending over the casing and the other toward the casing and adapted to fit over the 60 same, and the said inner ring being channel shaped, one wall thereof extending toward said casing and following the similar wall of said outer ring and offset therefrom at its edge to afford a packing groove coöperating with the edge of said casing, and the other wall of said channel shaped ring extending a short distance toward said casing to provide an abutment; a plate held between the wall of the outer ring extending over said casing and the said abutment; and a hinge, one leaf of which is secured to the two coöperating inwardly extending walls of the outer and inner rings and the other leaf to the said casing to hingedly connect 70 the cover thereto.

Signed at New York, in the county of New York, and State of New York, this 18th day of November, A. D. 1913.

WILLIAM H. BRISTOL.
